UNITED STATES PATENT OFFICE

2,429,706

METHOD FOR CREPING PAPER

Frederick P. Wood, Adrian, Mich., assignor to
Simplex Paper Corporation, Adrian, Mich., a
corporation of Michigan

Original application June 26, 1944, Serial No.
542,224. Divided and this application January
8, 1945, Serial No. 571,915

3 Claims. (Cl. 154—33.05)

1

The method of this invention involves the creping of paper in transit, while being continuously fed from a roll, by means of concurrently traveling crimpler bars which in close succession engage the paper surface along lines of spaced contact points which progressively draw closer together as the paper advances, thereby imparting minute crimps or indentations in the surface which render the completed strip elastic in all directions. This result can be attained either by an embossing or indenting action on the paper web or by a pinching action which produces minute folds, with a resultant narrowing of the web and both of these variations in the operation are deemed to be within the range of the present invention since the active crimpler bars are substantially the same in each case while a mere variation in the backing which supports the paper web will modify the nature of the compressive action imparted to the paper surface with a resultant difference in the crimping.

Further objects and details will appear from the following specification in conjunction with the accompanying drawings wherein:

Figure 1 is a side elevation, partly broken away, of one type of machine adapted to operate in conformity with the indenting principle of the present invention;

Figs. 2, 3 and 4 are details of one of the crimpler bars showing the positions it progressively assumes, and taken respectively on lines 2, 3 and 4 of Fig. 1;

Figs. 5 and 6 are enlarged details of a portion of one of the crimpler bars showing the teeth along its acting face in open and contracted relation respectively;

Fig. 7 is an end elevation of the machine looking toward the rear end of the machine into which the paper is fed;

Fig. 8 is a perspective detail of the connections for the ends of the crimpler bars;

Fig. 9 is a side elevation of a modified form of the indenting type of machine;

Figs. 10 and 11 are enlarged details of a type of crimpler bar for use on the machine of Fig. 9;

Figs. 12 and 13 are side elevations of two machines of modified form adapted to pinch the paper surface in the formation of minute plaits; and

Fig. 14 is a perspective view of the backing plate of the machine of Fig. 13.

The machine of Fig. 1 employs a backing drum 20 having a facing layer 21 of relatively soft yielding material such as rubber over which the paper web P is fed by the rotation of the drum which

2

is carried by a shaft 22 power driven in any suitable manner, as for instance by worm gearing 23.

The paper web is fed from under a roll 24 in advance of the forward end of the drum and is carried over and around the soft surface thereof so that contact is maintained throughout about 180°. The paper is progressively compressed into the soft surface of the drum by a multiplicity of closely spaced flexible crimpler bars 25 formed of relatively thin flexible steel or the like, which bars at their ends terminate in loops 26 connected by shackles 27 with the links of a pair of spaced endless chains 28. The chains are carried around front and rear pairs of lower sprockets 29 and 30 respectively, the front sprockets being mounted upon a shaft 31 and the rear sprockets upon a rear shaft 32. The lower sprockets cooperate with the front and rear pairs of upper sprockets 33 and 34 mounted upon shafts 35 and 36 which are journaled in any suitable manner.

Certain of the sprockets as, for instance, the rear sprockets 30 constitute the driving sprockets for imparting travel to the endless chains, the lower turns of which travel in arcuately converging relation to the surface of the drum and are slidable within guide members 37 mounted upon the frame of the machine.

The connection between the looped end of each 30 of the crimpler bars, and the shackle which connects it with the adjacent chain is of a character to permit a sliding movement in order to compensate for the flattening down of the crimpler bars as they approach the discharge side of the drum. The crimpler bars, which are initially bowed downwardly by contact with the under surface of a centrally disposed fixed shoe 38 will first make tangent contact with the drum surface at the center, and as the chains advance in registering surface speed with the drum, the crimpler bars will be progressively straightened out and will thereby progressively increase their surface contact with the paper web lying smoothly around the drum surface.

The front end 40 of the fixed shoe is looped upwardly to find support upon the shaft 31 while the rear end 41 is likewise looped upwardly to find support upon the shaft 32. Except for the looped ends, which simply serve as hangers, the shoe (or shoes) extends from front to rear of the backing plate, i. e. the peripheral surface of the drum, and in close proximity to its longitudinal center, the spacing being sufficient only to permit the relatively thin crimpler bars and the paper web to travel through the space thus afforded, with the

crimper bars in progressively increasing contact throughout with the upper surface of the paper web and progressively increasing the area toward the edges of the paper web which is being subjected to embossing pressure against the yielding surface of the drum.

As the lower turns of the chains pass around and under the forward lower sprockets, the middle of each crimper bar will in turn pass under the fixed shoe so that as the chains advance, the crimper bars will initially be bowed downwardly in the center to the maximum extent, and thereafter, as the chains continue to advance, the convergency of the chains running through the guides 37 toward the surface of the drum will cause the crimper bars to progressively straighten out as indicated in Figs. 2, 3, and 4, while at the same time establishing progressive contact with the paper surface which as it is embossed will by degrees draw in or narrow itself as a result of the indenting of its surface but without any tendency to rupture since the compressive embossure progresses gradually from the center toward the edges and by degrees which do not exceed the capacity of the paper web to withstand rupture.

The crimping is effected by teeth of the character indicated in Figs. 5 and 6. Each of the crimper bars is of sufficient thickness to permit the formation, in its under face, of teeth or bosses 42, the tips of which compressively engage the upper surface of the paper web and press the same into the surface of the drum. In the bowed or flexed condition shown in Fig. 5, the tips of the teeth will be spread apart to a greater degree than when the crimper bar is straightened as in Fig. 6, so that as the paper web advances, the teeth, in progressively increasing number, will make contact with the surface of the paper concurrently with its forward travel through the machine.

A doctor blade 43 serves to strip the paper from the side of the drum after which the paper web is wound up or otherwise disposed of.

In Figs. 9-12 I have shown a modified form of construction embodying the same general principle of operation, in which, however, the relative configuration of the drum and the crimper bars is reversed as compared with the arrangement first described.

In this construction, the rubber surfaced drum 44 is of barrel shape being bulged or convexly rounded outwardly around its center. The crimper bars 45 will initially lie flat and make tangent contact with the center of the drum surface and will be progressively flexed downwardly as they advance over and around the drum until at the discharge side they will be bowed or arched to the fullest extent so that as the paper is fed forwardly under the crimper bars, it will be carried up and over the bulging surface of the drum, and its edges progressively flexed downwardly in greater and greater degree as the area of contact between the crimper bars and the yielding drum surface is progressively extended.

In this instance I have shown crimper bars 45 formed of comparatively thin strips of flexible steel or the like which are corrugated to afford downwardly facing teeth or bosses 46 on their under faces and in this instance, in view of the fact that the crimper bars will be flexed downwardly as they advance, the teeth will be presented on the concave faces of the crimper bars and hence will contract as the concavity of the bars increases due to the progressive flexure. The ends of the bars are secured to chains 47 by

loops and shackles of the character first described, and the chains are mounted and driven in the same manner as in the case of the machine of Fig. 1. In this instance also the paper is stripped away by a doctor blade 48 which is curved to conform to the curvature of the backing plate at its discharge end.

The machines of Figs. 12 and 13 employ crimper bars and mountings therefor which are substantially identical with those previously described, but instead of a backing drum which rotates with the advancing crimper bars to establish a progressively increasing contact therewith, I employ a fixed backing plate having a surface contour 10 which is complementary to the contour collectively presented by the series of crimper bars while actively engaging the paper, so that the paper surface will be subjected to an overall compressive contact with the crimpers as it moves through the machine, while the teeth progressively contract in the manner first described and thus draw in the paper from the edges of the web in the formation of a multiplicity of folds or plaits running lengthwise of the paper web.

15 In order to thus maintain extended surface contact between the paper and the crimper bars, I provide a backing plate which may be configured like the plate 49 of Fig. 12 or like the plate 50 of Figs. 13 and 14. The plate 49 coacts with crimper bars, which, like those of the machine of Fig. 1, are initially bowed downwardly to the maximum degree and are serrated by teeth 51 which will be distended or spread apart to the maximum degree at the entering end 52 of the backing plate, which 20 is trough-shaped to maximum depth at this end, but which gradually flattens out toward its discharging end 53 to conform to the flattening down of the crimper bars as they travel above its surface and compress the paper web thereon and 25 thus draw in the paper from the edges of the web in the formation of a multiplicity of folds or plaits running lengthwise of the paper web.

30 35 40 45 50 55 60 65 70 75 In order to thus maintain extended surface contact between the paper and the crimper bars, I provide a backing plate which may be configured like the plate 49 of Fig. 12 or like the plate 50 of Figs. 13 and 14. The plate 49 coacts with crimper bars, which, like those of the machine of Fig. 1, are initially bowed downwardly to the maximum degree and are serrated by teeth 51 which will be distended or spread apart to the maximum degree at the entering end 52 of the backing plate, which is trough-shaped to maximum depth at this end, but which gradually flattens out toward its discharging end 53 to conform to the flattening down of the crimper bars as they travel above its surface and compress the paper web thereon and maintain overall compressive surface contact therewith from end to end of the backing plate.

With the toothed faces of the crimper bars thus in compressive engagement with the paper surface at all points, the teeth will gradually contract as the crimper bars are straightened out, and this will have the effect of progressively drawing in the paper toward the center, in the formation of minute folds or plaits which will gradually close up as the crimper teeth contract in the straightening out of the crimper bars.

In the machine of Figs. 13 and 14 the crimper bars and their mountings are arranged in a manner identical with that of the machine of Fig. 9, but in lieu of a rotating barrel shaped drum, I employ the fixed backing plate 50 which is flat at the end 54 where the paper enters and which is progressively arched upwardly in greater and greater degree, after the manner of an inverted trough, to conform to the progressively increasing flexure of the crimper bars which present their toothed acting faces downwardly to effect the closing or contracting of the teeth as the flexure of the crimper bars increases. The crimping or plaiting action, however, is substantially the same as that of the machine of Fig. 12, and it will be understood that other variations in the path of travel of the crimper bars can be introduced so long as provision is made for the closing of the crimper teeth in accordance with the principles of the present invention.

The machines of Figs. 12 and 13 provide a reliable method of imparting longitudinal crimps or minute plaits uniformly across the surface of a paper web, which is constantly contacted across its entire width by the crimper teeth throughout

a widely extended area. In either case the paper web will be drawn or fed through the machine by the pinching action of the advancing teeth, so that as the teeth contract, the web throughout will necessarily be under extended contact therewith, but the drawing in and resultant narrowing of the paper web will accrue gradually so that excessive and abrupt stresses which might tend to rupture the web are avoided. At the same time the feeding speed may be maintained at a high rate by the pull of the advancing crimpler bars without subjecting the paper web to feeding tension which, if applied, might tend to straighten out the crimps in the paper and thus impair its quality.

It will be understood that the various machines here described serve merely to illustrate and exemplify the principles of the present method which consists essentially in the provision of a multiplicity of toothed crimpler bars which, by their progressive flexure, serve to engage the paper surface, and thus crimp the paper.

This subject matter of this invention was first disclosed in my application filed June 26, 1944, Serial No. 542,224, now Patent No. 2,393,672, dated January 29, 1946 of which this case is a division.

I claim:

1. The method of creping a web of paper traveling over a supporting bed which consists in initially inwardly directing against the medial surface of the web only at points closely spaced longitudinally of the paper a plurality of closely spaced pressure contact points and thus indenting the medial area of the paper surface, and then progressively laterally increasing the acting number of such contacts and thus subjecting a laterally increasing area of the paper to indenture without displacing the longitudinal relation of said pressure contacts to the paper surface, and concurrently progressively reducing the transverse spacing of said pressure contact points as the paper advances.

2. The method of creping a web of paper traveling over a supporting bed which consists in initially creping the paper only at the center at

closely spaced points longitudinally of the web by a pinching action to form minute longitudinal folds with a resultant narrowing of the web and by simultaneously indenting the paper into a soft supporting surface to form transverse rows of indentations at said closely spaced points longitudinally of the web and then progressively increasing the creping action and the indenture uniformly transversely of the web until the entire surface of the web of paper is creped, thereby rendering the completed web of paper elastic in all directions.

3. The method of creping a web of paper traveling over a supporting bed which consists in initially inwardly directing only against the medial area of the surface of the web at points closely spaced longitudinally of the paper a plurality of pressure contact points to pinch the web between them and form minute longitudinal folds with the resultant narrowing of the web and simultaneously indenting the web to form transverse rows of indentations at said closely spaced points longitudinally of the web, and then progressively laterally increasing the active number of such pressure contact points and thus subjecting a laterally increasing area of the paper to said pinching action and indenture without displacing the longitudinal relation of the pressure contact points to the paper surface until the entire surface of the web of paper is creped, the pinching action and the indenture rendering the completed creped paper elastic in all directions.
